CHRISTMAS TREE ORNAMENT

Ramona McD. Trush, 67 Albany St.,
Cazenovia, N.Y. 13035

Filed Mar. 4, 1970, Ser. No. 21,734

Term of patent 14 years

Int. Cl. D11—05

U.S. Cl. D29—1

FIG. 4

FIG. 2

FIG. 1

FIG. 3

FIG. 5

FIG. 6

FIG. 1 is a front elevational view of a Christmas tree ornament showing my new design;

FIG. 2 is a side elevational view thereof as seen from the left of FIG. 1;

FIG. 3 is a side elevational view as seen from the right of FIG. 1;

FIG. 4 is a top plan view;

FIG. 5 is a rear elevational view; and

FIG. 6 is a bottom plan view.

I claim:

An ornamental design for a Christmas tree ornament, substantially as shown.
